UNITED STATES PATENT OFFICE.

AUGUSTINE R. AYERS, OF CHICAGO, ILLINOIS, ASSIGNOR OF ONE-HALF TO JOHN J. BERNET, OF CHICAGO, ILLINOIS.

LOCOMOTIVE-STOKER.

1,156,263.

Specification of Letters Patent.

Patented Oct. 12, 1915.

Original application filed May 26, 1913, Serial No. 769,840. Divided and this application filed August 20, 1914. Serial No. 857,635.

To all whom it may concern:

Be it known that I, AUGUSTINE R. AYERS, a citizen of the United States, and resident of Chicago, in the county of Cook and State of Illinois, have invented certain new and useful Improvements in Locomotive-Stokers, of which the following is a specification.

My invention relates to locomotives and has particular reference to novel fuel feeding means for use in connection therewith.

This application is a division of my application, Serial No. 769,840, filed May 26, 1913.

In the chain-grate as ordinarily installed, that is, in stationary practice, coal is fed to the grate through a hopper located above the grate, and distribution of the coal throughout the full length of this hopper, in other words, over the full width of the grate, is obtained by hand-shoveling or by gravity feed, the coal in the latter case being fed from storage hoppers located considerably above the grate. It is my purpose to avoid practically all hand-shoveling, and the construction of locomotives is such that gravity feed is not at all practical, the coal supply on the tender being carried at a height very little above the level of the grate. In the arrangement shown, the coal is conveyed from the tender to the transverse center of the grate at the rear end thereof and is delivered into a space in which transverse spreaders are mounted.

These spreaders act to distribute the fuel over the width of the grate and are adjustable vertically, whereby the thickness of fuel can be varied and controlled over the entire width of the grate. This is an important feature, inasmuch as it is quite necessary at times to provide a deeper fire over one portion or another of the grate. This may be accomplished by different means; preferably conveyers or deflectors are provided, which are adjustable vertically from either end, two of such deflectors being mounted at the sides and transverse center of the grate. Each of such deflectors being mounted for vertical adjustment, the height of the fuel may be controlled exactly. Not only may the transverse conveyers be adjusted bodily but their outer ends may be adjusted independently of their inner ends. Furthermore I prefer to employ in connection with the screw conveyers a flat vertical plate located

forwardly of the conveyers and adapted to 55 level the coal which passes therebeneath, an even distribution of the material being secured thereby.

The connection between the locomotive and the tender is of necessity a flexible one. 60 Preferably also the driving means for the conveyer which carries the coal from the tender to the grate should be connected to the conveyer at the rear end. If the driving means for the conveyer is connected to 65 the forward end of the conveyer the mechanism therefor would seriously encroach upon the available space at the point of discharge of the fuel and would hamper the discharge and distribution thereof. Furthermore, the connection between the conveyer and the engine must be a slidable and flexible one. This further increases the difficulty of driving from the front end of the conveyer. In my construction I locate the 75 driving means for the conveyer at the rear end thereof where the space is ample, providing a universal and sliding joint in the shaft between the engine and the tender. By this means the driving connections may be 80 located beneath the chute on the engine and be entirely out of the way, permitting a very flexible connection between the conveyer and the engine. Furthermore, by the means shown I am enabled to feed from the 85 bottom of the tender directly to the distributing space.

The invention will be more readily understood by reference to the accompanying drawings, wherein,

Figure 1 is an elevation partly in section showing an engine tender and a portion of the deck of a locomotive, my novel fuel feeding means having been applied thereto; Fig. 2 is a section on the line 2-2 of Fig. 1; Fig. 95 3 is a plan view of a portion of the grate of a locomotive showing the means for delivering fuel thereto; Fig. 4 is a side elevation of the same construction; Fig. 5 is an enlarged detail end elevation of the transverse 100 distributors; Fig. 6 is a fragmentary front view thereof; and Figs. 7 and 8 are views of the hand lever by means of which the supply of fuel to the feeder and crusher rollers is controlled.

Referring more particularly to the drawings it will be seen that within the tender 10 is provided a hopper 11, having an opening

12, therethrough, which opening is controlled by a sliding gate 13, actuated by the rack 14, controlled by the handle 15, and movable in opposite directions by means of the pawl and ratchet mechanism 16, 17. This handle is available to the fireman and the amount of fuel fed may be controlled through this means. Beneath the opening 12, are a pair of feeder and crusher rolls 10 mounted in suitable bearings and actuated through the gearing 18, chain 19, and shaft 20, which will later be described. Mounted beneath the crushers is a chute 21, having an open-topped, hopper-like rear end 22. This chute extends from a point beneath the crushers 17, to the fuel distributing space in the locomotive. Mounted within the chute is a screw conveyer 23, connected through the universal joint 24, to a beveled gear 25. The gear 25 is actuated indirectly by means of a worm 26, on the shaft 20. The forward end of the screw conveyer is mounted in a bearing carried by a yoke 27 secured to and movable with the chute 21. As shown in Figs. 1 and 3, the chute passes freely through an opening formed in a plate 28, which constitutes one wall of the coal receiving space above the grate 29.

The shaft 20 is provided at its forward end with a universal joint 30 and has a sliding connection 31 with a stub shaft 32, also provided with a universal joint 33, connected by suitable beveled gears, to a transverse shaft 34, connected at the side to the longitudinal power shaft 35.

The coal is delivered to the space above the grates in a suitable condition and in proper quantity. The coal is thereafter distributed and fed by means of the transverse spreader, best shown in Figs. 3, 4, 5 and 6. Connected to the rear leg of the boiler are brackets 36, 37, 38, each of which carry an adjusting screw 39, operatively connected to a vertically movable guiding member 40, fitted within ways 41, within the brackets 36, 37, 38. Operatively connected to the member 40 is a bar 42, which constitutes a vertical plate acting to level the fuel as it passes therebeneath. Secured to the bar 42 are bearings 43 within which the shaft of a screw conveyer 44 is mounted. At the middle, as shown in Fig. 6, the two adjacent ends of the bars 42 are pivoted to the member 40 by means of a single pin 45. It will be seen that the distributing devices may be adjusted at their free ends to distribute the fuel in any desired manner over the grate. A high fire may be provided at the center or at either side as desired. The transverse conveyers are driven by means of chains 46, meshing with sprockets carried on the ends of a transverse shaft 47, operated from the power shaft 35. In view of the fact that the plates 42 and the conveyers 44 move vertically in unison, the fuel is properly dis-

tributed and fed to the grate in an even layer which is a decided advantage.

The construction is capable of considerable modification, the points of interest in the present invention consisting in providing the drive for the conveyer at the rear thereof and in the tender thus keeping the front end clear of mechanism; also in providing a universal and sliding joint between the tender and engine; also in providing a distributing device which is capable of vertical adjustment in any form conducive to the production of the best fuel layer on the grate.

I claim:

1. In a device of the class described, the combination with a locomotive of an endless grate, means for supplying fuel to said grate, and means for distributing said fuel over the surface of said grate, said means including vertically-adjustable deflectors located at the point of fuel supply and means for vertically adjusting each end of each deflector, substantially as described.

2. In a device of the class described, the combination with a locomotive of an endless movable grate, means for supplying fuel to said grate at one end thereof, a pair of deflectors located at the point of fuel supply, and means for vertically adjusting both ends of both said deflectors, whereby to control the height of fuel fed to said grate, substantially as described.

3. In a device of the class described, the combination with a locomotive of an endless movable grate, means for supplying fuel to said grate at one end thereof, and a pair of screw conveyers vertically adjustable and arranged for rotation, whereby to distribute fuel over the surface of said grate, substantially as described.

4. In a fuel feeding device, the combination of a pair of transverse spreaders, means for moving said spreaders independently at the outer ends thereof, and separate means for vertically moving both said spreaders at the adjacent ends thereof, substantially as described.

5. In a fuel feeding device, the combination of a moving grate, a pair of transversely arranged spreaders, a leveling plate associated with said spreaders, and means for vertically adjusting said spreaders and plate, substantially as described.

6. In a device of the class described, the combination with a locomotive, of an endless, movable grate, means for supplying fuel directly to the surface of said grate and in substantially the plane of the top of said grate, and means for distributing and spreading the fuel in substantially the same plane in which it is delivered to the grate.

7. In a device of the class described, the combination with a locomotive, of an endless chain grate, a coal conveyer discharg-

- ing coal upon said grate at its transverse center near the rear end, and a pair of transverse spreaders, said spreaders being located immediately adjacent the mouth of the conveyer and adapted to distribute the fuel over the entire width of said grate, the lower edge of said conveyer being located substantially at the top surface of the fuel bed.
8. In a device of the class described, the combination with a locomotive, of an endless chain grate, means for delivering coal directly to the surface of said grate at its transverse center and beneath the firing deck
- 5 of the locomotive, and means located immediately adjacent to the coal delivering means 15 for distributing said coal over the full width of said grate, said distributing means being located above the surface of the grate and beneath the firing deck of the engine.
- Signed at Chicago, Ill., this 15th day of 20 August, 1914.

AUGUSTINE R. AYERS.
